Attorney.

UNITED STATES PATENT OFFICE.

ABRAHAM G. GARDINER, OF PROVIDENCE, RHODE ISLAND.

NIPPLE.

1,176,674.

Specification of Letters Patent. Patented Mar. 21, 1916.

Application filed July 1, 1915. Serial No. 37,407.

To all whom it may concern:

Be it known that I, ABRAHAM G. GARDINER, a citizen of the United States, residing at Providence, in the county of Providence and State of Rhode Island, have invented certain new and useful Improvements in Nipples, of which the following is a specification.

My invention relates to nipples intended for use upon nursing bottles, and has for its essential objects, the prevention of the stoppage of the nipple passage, by accumulation of air at the base thereof and the passage therethrough of an excess of air heretofore occasioned by the collapsible character of the mouth piece; to provide a universal movement in any direction of the mouth piece, relatively to the neck or head of the bottle; to expose a minimum surface of soft rubber to the action of the milk; to insure sanitation by the ready disassemblage of all the parts; to provide a structure adaptable to use upon bottle necks of various sizes; and to attain these ends in a simple, inexpensive, and essentially operable structure.

To the above ends essentially my invention consists in such parts and combinations of parts as fall within the scope of the appended claim.

In the accompanying drawings, which form a part of this specification, Fig. 1 is a side elevation of the novel nipple applied to the neck of a bottle. Fig. 2, a vertical central section of the same, Fig. 3, a section on line 3—3 of Fig. 2, and Fig. 4, a section similar to that shown in Fig. 2, wherein the mouth piece of the nipple is shown in an inclined position.

Like reference characters indicate like parts throughout the views.

My invention is shown as applied to the rim a of the neck A of an ordinary glass nursing bottle.

In detail my device comprises an elastic cap or hood B having a rounded or swelled side wall b , a retracted bottom portion b' , and a dome shaped top wall b^2 provided with a central opening b^3 .

Resting upon the top of the described cap is a solid nipple or mouth piece C of hard rubber or similar non-elastic and non col-

lapsible material having a rounded free end portion c , a retracted intermediate portion c' , and a bottom portion c^2 of enlarged diameter having its bottom face concaved or provided with a curved cavity c^3 to accommodate the material of the dome b^2 of the cap. Within the cavity concentric therewith is a circular projecting internal shoulder c^4 having a flat bottom face resting upon the cap. The mouthpiece has a central longitudinally disposed passage d for the passage of the milk, which is of enlarged diameter at its lower portions forming a cylindrical cavity d' bounded by a thread d^2 engaging a thread e upon the exterior of a plug E seated in the cavity and passing through the hole b^3 in the cap. A flat head e' upon the lower end of the plug presses against the lower face of the cap dome and is forced by the coöperation of the threads so tightly thereagainst as to be perfectly air and liquid tight. The plug is provided with a central longitudinal passage e^2 of a diameter corresponding to the passage d and registering therewith.

The elastic character of the soft rubber cap B and its retracted lower portion permits its tight application to bottle rims or necks of various sizes, while the dome shaped upper portion of the cap allows ample material for the tilting movement of the mouth piece C without excessive strain upon the elastic material. The threaded plug E which is of hard rubber may by the manual turning thereof be removed from the members B and C to allow cleansing of the parts. The member C is capable of assuming a tilted or angular position in all directions and to any reasonable degree of depression to accommodate the whim of the user. The base c^2 , forms in conjunction with the rim of the bottle, a stop to an excessive degree of tilting and forms a protective shield for the dome portion of the cap.

What I claim is:—

In a nipple, the combination of an elastic cap provided with a central opening, a solid mouth piece comprising a rounded free end portion, a restricted intermediate portion, and a bottom portion of enlarged diameter provided concentrically in its bottom face with an annular cavity to permit free move-

ment of the cap and mouth piece when the latter is tilted, a downwardly projecting shoulder integral with the bottom portion of the mouth piece within the cavity and resting upon the top of the cap whereby the mouth piece is partially spaced from the cap,

and a member in the mouth piece traversing the opening and engaging the inner face of the cap.

In testimony whereof I have affixed my signature.

ABRAHAM G. GARDINER.
